Attorney

UNITED STATES PATENT OFFICE

ANTONIO PELOSI, OF BROCKTON, MASSACHUSETTS

ARTICLE CARRIER

Application filed March 14, 1929. Serial No. 347,127.

This invention relates to an article carrying and securing device designed primarily for use by students, though applicable to many other uses.

5 The primary object of this invention is to provide a device which may be employed for securing together a number of books or a number of other articles or for holding a rolled article in a bundle and having means 10 associated therewith whereby an assortment of small articles may be supported and carried with the device ready for use when needed.

The invention broadly contemplates the 15 provision of a relatively long and broad body of flexible material preferably leather having one face provided with a longitudinally extending series of loops each of which may receive an article. At one end of the leather body a transverse slit is formed therethrough and adjacent the slit on the back or outer face of the body a buckle is secured. Adjacent the opposite end of the body there is secured thereto a relatively long strap which 25 after being passed about an article or a number of articles held by the device, engages the buckle for maintaining the article or articles in a neat bundle or pack.

A further object of the present invention is 30 to provide a device of the above described character which may be economically constructed, which will be strong and durable and which will be efficient for the purpose described.

35 The invention will be best understood from a consideration of the following detailed description taken in connection with the accompanying drawings forming a part of the present invention with the understanding, however, that the invention is not confined to any strict conformity with the showing of the drawings but may be changed or modified so long as such changes or modifications 40 mark no material departure from the salient features of the invention as expressed in the appended claim.

In the drawings:—

Figure 1 is a plan view of the inner face of 45 the article carrier embodying this invention;

Figure 2 is a view showing the article applied;

Figure 3 is a sectional view taken on the line 3—3 of Figure 1.

Referring to the drawings in detail the 55 numeral 1 indicates generally the body of the present device which as shown, comprises a relatively long broad strip of material of a flexible nature, preferably of leather.

This body is cut square across at one end 60 as indicated at 2 and at its opposite end has the corners cut away obliquely as indicated at 3 to form a pointed end portion and overlying a part of this pointed portion upon one face of the body is a reinforcing sheet 4 of 65 the same material stitched about its edges to the main body 1 as shown, and having the central part thereof open as indicated at 5.

Secured to the main body 1 of the device beneath the sheet 4 to appear through the 70 opening 5, is a mirror 6.

Extending from the reinforcing sheet 4 longitudinally of the inner face of the body 1 is a strap 7 which is stitched transversely at a number of points as indicated at 8 to the 75 main body forming a series of loops 9 beneath each of which an article may be slipped to be carried by the body. As shown, the loops may be employed for holding pencils, a ruler, eraser, or similar articles when the 80 device is used by school children.

Adjacent its end 2 the body has formed therethrough, a slit 10 through which the adjacent end of the strap 7 extends to the back of the body 1 where it carries a buckle 85 11. A reinforcing body 12 is secured to the body 1 over the slit 10 in the manner shown, that edge of the reinforcing body adjacent the strap 7 being free of the carrying body.

At its other end the main body 1 has attached thereto, preferably under the edge of the reinforcing sheet 4, one end of a relatively long strap 13 the free end of which is designed to be engaged by the buckle 11 when the device is in use. 90

As previously stated, the present article carrying and holding device is designed primarily for the use of school children and as illustrated in Figure 2 it may be employed for securing together a number of books in 100

place of the usual book strap and when so employed the face of the body 1 carrying the looped strap 7 is directed toward the books which the device holds together.

5 It is, of course, obvious that this device may be employed for a number of other purposes as for example, it may be used as a traveling case, in which case, the loops 9 may be made of a size to conveniently take a
10 brush, comb, soap box, etc., and the device may be secured about a towel or similar article to maintain the same in a compact roll.

Having thus described my invention, what I claim is:—

15 An article carrier of the character described comprising an elongated flexible member, a pair of strap sections secured to said flexible member and extending longitudinally thereof, one of said strap sections
20 having the free end thereof positioned oppositely from the free end of the other strap section and on the opposite side of said flexible member, stitching positioned transversely of one of said strap sections and engaging
25 said flexible member whereby to provide a plurality of pockets longitudinally of said flexible member, a buckle carried by one of said strap sections, said strap sections upon engagement with each other and about a folio
30 being adapted to restrict said pockets whereby to securely hold an article within said pockets.

In testimony whereof I hereunto affix my signature.

35 ANTONIO PELOSI.
